FREDERICK C. WESTFALL, OF EAST SYRACUSE, NEW YORK, ASSIGNOR TO T. N. BENEDICT MFG. CO., OF EAST SYRACUSE, NEW YORK, A CORPORATION OF NEW YORK.

PUMP FOR BEVERAGE-DISPENSING MACHINES OR FOUNTAINS.

1,361,943.

Specification of Letters Patent.

Patented Dec. 14, 1920.

Application filed April 12, 1915. Serial No. 20,647.

To all whom it may concern:

Be it known that I, FREDERICK C. WESTFALL, a citizen of the United States, and a resident of East Syracuse, in the county of 5 Onondaga and State of New York, have invented a certain new and useful Pump for Beverage-Dispensing Machines or Fountains, of which the following is a specification.

10 This invention has for its object a pump for beverage dispensing machines as soda water fountains and the like, which is particularly simple in construction and highly efficient in use, and it consists in the combinations and constructions hereinafter set forth and claimed.

In describing this invention, reference is had to the accompanying drawings, in which like characters designate corresponding parts 20 in all the views.

Figure 1 is a longitudinal sectional view of this pump.

Fig. 2 is a section on line A—A, Fig. 1.

This pump for beverage dispensing machines comprises, generally, a barrel, a tube mounted on the barrel substantially in axial alignment therewith, and opening at its lower end toward the interior of the barrel, an outlet pipe running along the tube and being joined thereto and extending into the barrel, and a plunger movable in the barrel and having a stem extending into the tube and a handle or head at its upper end.

The pump further includes, generally, a block mounted on the upper end of the tube and having a nozzle the passage of which is aligned with the outlet pipe, and a top plate for covering the receptacle in which the pump is located.

40 1 designates the barrel which has a removable bottom 2 threading thereinto, the barrel having inlet openings near its top. As here shown, the top is composed of inwardly converging arc-shape arms 3 in the form of 45 a spider.

4 is the tube mounted on the top of the barrel 1 at the juncture of the arms 3, the tube extending through the top so that it opens into the interior of the barrel 1. The 50 tube is provided with a lining 5 and a casing 6 of non-corrosive material.

7 is the outlet pipe running lengthwise of the tube 4 and usually joined thereto, said pipe extending through one of the arms 3

and into the barrel 1 and terminating near 55 the bottom of the barrel.

8 is the plunger movable in the barrel, the plunger being formed with an opening 9 through which the outlet pipe 7 extends.

10 is the stem of the plunger which extends upwardly through the tube 4 and above the top plate and the block to be described. 60 11 is the handle threading on the upper end of the stem. The portion of the stem 10 which comes in contact with the syrup or 65 other liquid in the tank is covered by a sleeve or casing 12 of non-corrosive material. The stem is of considerably less diameter than the tube and hence there is a comparatively large space between the stem and the 70 inner wall of the tube for facilitating cleansing.

13 is the top plate, and 14 is the block or casting which is formed with a passage 15 aligned with and receiving the tube 4. The 75 block 14 is also formed with a nozzle 16 the passage of which is aligned with the passage of the pipe 7. The upper end of the pipe 7 is deflected at 17 away from the tube 4 and is joined at 18 to the top plate. The 80 casing 6 of the tube 4 terminates at the top plate.

19 is a sleeve encircling the stem 10 and spaced apart therefrom and fixed to a head 20 threading on the stem below the handle 11, the sleeve extends into a tube 21 fitted into the upper end of the tube 4. Said head 20 is formed with a central socket in which a reduced extension of the handle is preferably secured so that the head and 90 handle move as one piece. The tube 21 is formed with an external annular flange 23 at its upper end which extends over and forms a facing for the edge of the tube 4 and surrounding portion of the block 14 95 and with an inturned flange 24 at its lower end forming a seat for a spring 25 interposed between said flange 24 and the head 20.

In use, the pump is arranged in the syrup container or tank of which the top plate 100 13 is the cover, and the spring 25 holds the plunger elevated against shoulders 26 on the arms 3 so that there is space below the plunger for the syrup to flow into the barrel 1.

In operation, the operator depresses the plunger and forces the syrup in the barrel up through the pipe 7 and nozzle 16, and if

desired the throw of the plunger and hence the amount of the syrup delivered can be regulated by turning the head 20 toward or from the flange 23.

5 This pump is particularly advantageous in that it can be readily removed as a unit from the tank and upon the removal of the bottom 2 and the plunger 8, the tubes 4 and 7 can be quickly and thoroughly cleansed 10 owing to the central location of the tube 4.

I claim—

1. A beverage dispensing machine pump comprising a top plate formed with openings, a nozzle having a base mounted on 15 the top plate and having openings alined with the former openings, a tube extending through one of the openings of the top plate and through the alined opening of the base, the base being mounted on the tube 20 above the plate, an outlet pipe extending through the other opening of the base and communicating with the outlet passage of the nozzle, and an operating rod extending through the tube, substantially as and for the 25 purpose described.

2. A beverage dispensing machine pump

comprising a top plate, a nozzle having a base mounted on the top plate, the base and the plate being formed with alined openings, a barrel, a tube rising from the barrel 30 and extending through alined openings of the base and the top plate, the base being mounted on the tube above the plate, an outlet tube communicating with the nozzle, an abutment consisting of a tube extending 35 into the upper end of the first mentioned tube, and having an inturned shoulder at its lower end, a plunger movable in the barrel and having a stem extending through the tube, a handle at the upper end of the stem, 40 and a spring interposed between the handle and the shoulder of the abutment, substantially as and for the purpose specified.

In testimony whereof, I have hereunto signed my name in the presence of two attesting witnesses, at East Syracuse, in the county of Onondaga, and State of New York, this 3d day of Feby., 1915.

FREDERICK C. WESTFALL.
